Attorney.

UNITED STATES PATENT OFFICE.

FRANK REED, OF OMAHA, NEBRASKA.

WHIFFLETREE.

No. 892,622.

Specification of Letters Patent.

Patented July 7, 1908.

Application filed August 7, 1907. Serial No. 387,551.

To all whom it may concern:

Be it known that I, FRANK REED, a citizen of the United States, and a resident of Omaha, in the county of Douglas and State 5 of Nebraska, have invented certain new and useful Improvements in Whiffletrees, of which the following is a specification.

My invention relates to whiffletrees or other wagon and carriage draft members, 10 and it is the object thereof to provide a light, strong and cheaply constructed whiffletree or the like, made entirely of metal.

The invention consists in the details of construction by which a slighty appearance 15 and a maximum of strength are secured with the use of a minimum weight of material.

In the accompanying drawings Figure 1 is a plan view of a doubletree and swingletrees embodying my invention, Fig. 2 is a trans- 20 verse section through the end of one of the swingletrees, Fig. 3 is a transverse section through the center-block of the doubletree, Fig. 4 is a bottom plan of the central portion 25 of the doubletree, and Fig. 5 is a transverse section through one end of the doubletree and the center of one of the swingletrees.

In carrying out my invention I construct both the doubletree and swingletrees in the form of a truss made up of front and rear 30 members formed of rolled-steel sections having both horizontal and vertical flanges, the said rolled-steel members being connected at the center and ends of the truss by cast members, preferably of malleable iron or 35 cast-steel. In the drawings said rolled-steel members are shown as formed of angle iron, but other sections, such as channel- or T-iron, having flanges at right angles with each other, may be employed. The front 40 members 1 of each of the trusses are straight from end to end, one flange of the section being disposed in a vertical plane and the horizontal flange of the section extending rearwardly from the upper edge of the vertical flange. The rear member 2 of each 45 truss is slightly bent at its center in a horizontal plane, the vertical flange being at the rearward side thereof and the horizontal flange extending forwardly from the upper 50 edge of the vertical flange.

The center-block 3 of the double-tree is made to fit between the front and rear truss-members 1 and 2, being secured thereto by rivets 4 passing through the horizontal 55 flanges and rivets 5 passing through the vertical flanges of said members. The under

side of the said block 3 has recesses 6 therein near its front and rear edges to permit the placing of the rivets 5, and on the upper side of the block at the center thereof is a boss 60 through which is a vertical opening 7 to receive the wagon-hammer. The end blocks 8 of the doubletree are secured between the vertical flanges of the truss-members 1 and 2 by rivets 9 passing through both flanges and 65 the block, and to each of the horizontal flanges thereof by rivets 10. On both the upper and lower sides of said end blocks are small bosses through which pass the pins of the clevises 11. Said clevises 11 connect 70 with the twisted links 12 which pass through the openings of the center-blocks 13 of the swingletrees. The said center-blocks 13 are secured to the front and rear truss-members 1 and 2 by rivets 14 extending through the 75 horizontal flanges and rivets 15 extending through the vertical flanges of said members, similarly to those securing the center-block 3 of the doubletree.

At the ends of the swingletrees the blocks 80 16 are secured by rivets 17 passing through both of the vertical flanges and rivets 18 passing through each of the horizontal flanges of the members 1 and 2. At the centers of the end-blocks 16 are openings for 85 the trace-hooks 19, the horizontal flanges of the members 1 and 2 having small notches in the adjacent edges thereof, as shown in Fig. 2, to complete said openings.

It will be apparent that, by the construction shown, a light, strong whiffletree may be made at a low cost, the rolled-steel truss-members having both horizontal and vertical flanges and securely connected with each other and with the center- and end-blocks 95 90 by rivets passing through both the horizontal and vertical flanges thereof, making a device in which a high resistance to bending stresses is secured with small weight of material and low cost of assembling the parts. It should 100 also be noted that, by the construction shown, either doubletree or swingletrees are interchangeable with the wooden whiffletree-members in ordinary use, so that the swingletrees may be used with a wooden 105 doubletree, or the reverse.

Now, having described my invention, what I claim and desire to secure by Letters Patent is:

1. A whiffletree comprising a front member and a rear member formed of rolled-steel sections having horizontal and vertical

flanges, a cast center-block secured between the central parts of the front and rear members, cast end-blocks secured between the ends of the front and rear members, and 5 means connecting said center- and end-blocks with both the horizontal and vertical flanges of the front and rear members.

2. A whiffletree comprising a straight front member formed of a rolled steel section having horizontal and vertical flanges, a centrally-bent rear member formed of a rolled-steel section having horizontal and vertical flanges, a center-block secured between said front and rear members, end-blocks secured 10 between said front and rear members, and rivets connecting said center- and end-blocks with both the horizontal and vertical flanges of both the front and rear members. 15

3. A whiffletree comprising a straight front member and a centrally-bent rear member each formed from a rolled steel angle bar, 20 the horizontal flanges of the two angle bars being turned toward each other, a cast center-block and end-blocks disposed between the two angle bars, and rivets connecting each of said end-blocks and the center-block 25 with both the horizontal and vertical flanges of both the front and rear angle bars.

In testimony whereof I have hereunto subscribed my name in the presence of two witnesses. 30

FRANK REED.
